In Great Britain December 21, 1939

13 Claims. (Cl. 101—132.5)

This invention relates to duplicating machines in which a copy sheet and a master sheet bearing in reversed script the matter to be reproduced are passed in pressure contact between a cylinder which carries the master sheet and a pressure roller, said copy sheet being moistened before being brought into contact with the master sheet.

More particularly the invention has reference to the type of duplicating machine in which provision is made for moistening the copy sheets sectionally, so that when a master sheet is secured to the cylinder with the lines of writing thereon extending circumferentially of the latter, the matter reproduced on the copy sheet may be confined to any one or more of such lines.

One of the objects of the present invention is to provide a machine whereby any selected item from the master sheet may be reproduced on the copy sheets.

A further object of the present invention is to construct the machine so that a plurality of items selected from the master sheet may be reproduced on the copy sheet simultaneously.

A further object of the present invention is to provide improved means for controlling the amount of moisture imparted to the copy sheets.

A further object of the present invention is to provide improved means whereby the pressure of the pressure roller or rollers may be adjusted.

A further object of the present invention is to provide a simple and relatively inexpensive construction of machine wherein the parts can be readily produced and assembled, and wherein ready access is obtainable to all those members which have to be operated for making adjustments.

Referring to the drawings:

Figure 1 is a perspective view showing one construction in accordance with this invention.

Figure 2 is a view in front elevation showing one of the pressure rollers.

Figure 3 is a view in front elevation showing another pressure roller element of different form.

Figure 4 is a perspective view showing one of the moistening pads and its casing.

Figure 5 is a plan view of the machine with certain parts omitted for the sake of clearness.

Figure 6 is a section on line 6—6 of Figure 5.

Figure 7 and 7^a is a section on line 7—7 of Figure 5.

Figure 8 is a plan view of a machine with certain parts omitted, wherein the mechanism for moving the carriage is similar to that provided on a typewriter.

Figure 9 is a section on line 9—9 of Figure 8.

Figure 10 is a plan view showing the operating key and certain associated parts for moving the carriage in one direction with a step by step movement.

Figure 11 is an end view partly in section showing a portion of the mechanism for travelling the carriage.

Figure 12 is a front view showing the mechanism employed for moving the carriage with a step by step movement in the direction opposite to that in which it is pulled.

In both constructions illustrated the machine comprises a frame having two end plates 10 connected in the usual way by tie rods 11. At the top each end plate is provided with an upwardly extending cheek plate 12. These plates 12 may be made integrally with the plates 10 if desired.

The cylinder 13 which is adapted to carry the master sheet indicated at 14 is mounted upon a shaft 15 which may be driven by hand or by an electric motor. The cylinder is provided with a clamping device indicated generally at 16 for holding one end of the master sheet.

One end of the cylinder is provided with an extension 17 having a notch 18 in its periphery which is engaged by a roller 19 when acted upon by a spring so as to provide a check to the rotary motion of the cylinder 13 once every revolution.

Further, each end of the cylinder is provided with a cam 20 for the purpose of raising and lowering periodically the pressing member employed to press the copy sheets on to the moisteners.

Extending between the plates 10 is a bar 21, and in the construction shown in Figures 1 to 7 this bar is in the form of a rotatable shaft provided with a helical groove 108.

In the construction shown in Figures 8 to 12, however, the bar is fixed and has no groove.

Extending between the plates 12 is a bar 23 of square section.

A carriage is provided which is movable in a direction parallel to the axis of the cylinder 13, and this carriage comprises a tank 24 carrying a frame 25 which supports a feed tray 26. The carriage also includes a box 27 connected to the tank by means of a side plate 28.

The box 27 includes a second side plate 29, a top plate 30, a front plate 31 and a rear plate 32. The box also includes a bar 34 connecting the side plates 28 and 29.

The plate 30 and the bar 34 carry adjustable stems 35 and 36 each of which includes a fork 37 containing a roller 38 each mounted for rotation on a pin carried by its fork.

The carriage is supported and guided for movement parallel to the axis of the cylinder by the bar or shaft 21 which passes through the tube 29 and a bar 23, the ends of which are connected to the plates 12 of the machine frame. The upper and lower sides of the bar 23 are flat and are engaged by the rollers 38.

In the constructions shown there are two pressure roller elements. These are shown in

Figures 2 and 3, and it will be seen that the roller 40 in the element shown in Figure 2 is wider than the rollers 41 shown in Figure 3. The rollers 41 may be of line width, in which case the roller 40 is of the width of two lines.

In the matter to be copied usually most of the items occupy only one line, but the heading, or perhaps some other part of the matter, may occupy two or more lines. The roller 40 will generally be suitable for replacing a heading which is generally two lines, and the rollers 41 are each capable of operating for one line.

As will be seen from Figure 7, each pressure unit comprises a roller mounted upon a pin 42 carried by a fork at the lower end of a rectangular sectioned stem 43. This stem can slide in a vertical groove in a block 32 detachably secured to the plate 31, there being a plate 33 secured across the front of the groove. Each of the stems 43 has a shoulder 44, above which the stem is reduced and is of cylindrical form. The upper ends of the stems pass through a threaded guide 45 and also pass through a plate 46 fixed to the top of the block 32. The threaded guide 45 is provided with a flange 47 beneath the plate 46, and above the plate 46 a knurled head 48 is provided on the threaded guide so that it can be turned on its own axis.

Mounted on the exterior of the threaded guide is an adjustable nut 49 having a radially projecting screw 50 projecting through a vertical slot 51 in the plate 33.

A spring 52 acts between the nut 49 and the shoulder 44, and the arrangement is such that the pressure of the spring can be adjusted by turning the knurled head 48 so as to raise or lower the nut 49.

At the projecting top of the stem lock nuts 53 are provided which form an abutment to limit the downward movement of the stem 43 and of the pressure roller.

Acting between the underside of the lock nuts and the upper side of the knurled head 48 is a forked lever 54 pivoted at 55 to lugs 56 on the block 32, and this lever is provided with a finger piece 57.

One edge of the stem 43 is provided with a notch 58 adapted to be engaged by a plunger 59 acted upon by a spring 60, the plunger 59 being carried by a stem 61 having a head 62. The arrangement is such that when the lever 57 is pushed downwardly the corresponding pressure roller is raised and is retained in the raised position by reason of the fact that the plunger 59 engages in the notch 58. The pressure roller can be lowered into its working position again by pulling the head 62 thus disengaging the plunger 59 from the recess 58 in the stem 43.

The end plates 12 of the machine are provided with a tray 63 having adjustable clips 64 whereby a line indicator sheet may be carried in proximity to the finger pieces 57. When a finger piece 57 is depressed it places out of action one of the pressure rollers, and those finger pieces 57 which have not been depressed co-operate with the line indicator so that the operator can see which of the lines on the master sheet are being reproduced.

As will be seen clearly from Figure 7, at one position the cylinder 13 is provided with a longitudinal recess 65 which corresponds with the position of the pressure rollers at the position when the rotation of the cylinder is checked by the roller 19 engaging in the recess 18. The provision of this recess enables the copy sheets 66

to be passed in freely between the pressure rollers and the cylinder, and further, it enables the carriage to move freely parallel to the axis of the cylinder with the pressure rollers out of contact with the periphery of the cylinder.

A tank 24 is provided at the top with a platform 67, and between the tank and the platform is an opening 68 through which projects a wick 69. The upper end of the wick is fixed to a cam 70 rotatable upon a spindle 71 which can be turned by a handle 72 from the exterior of the tank, the arrangement being such that the upper part of the wick can be raised and lowered thereby in and out of contact with the moistening pads, one of which 73 is seen in Figure 7. As the spindle 71 is turned clockwise (Figure 7), the area of contact between the wick 69 and the pads 73 is reduced and further movement of the spindle 71 gradually decreases the pressure between the wick and the pads. Finally the wick is moved out of contact with the pads.

Each moistening pad is made of absorbent material and is mounted in a metal casing 74 having a handle 81, the arrangement being such that the moistening pad slides on the platform 67 and under a plate 75 into and out of its operative position. In Figure 7 the moistening pad 73 is shown in the operative position, but it can be pulled to the right so that it will not make contact with the copy sheet 66.

The tank is further provided with a tubular filler tube 76.

It will be understood that the number of moistening pads corresponds with the number of pressure rollers. If it is desired to reproduce only one line or item from the master sheet on the cylinder then the moistening pads corresponding with lines not to be reproduced are moved into the inoperative position.

In the construction illustrated there may be two moistening pads, one co-operating with the pressure roller 40 and the other co-operating with the pressure rollers 41, but if required there may be three, in which case there will be separate moistening pads for the two rollers 41.

It is necessary to press the copy sheet 66 down on to the moistening pad, or down on to any moistening pads that are in the operative position, and for this purpose a bar 77 is provided carried by a pair of levers 78 pivoted at 79 to the ends of the carriage. These levers 78 are acted upon by springs 80, each acting between a bracket 81 and the top of a pressure block 82 bearing on the upper side of the lever.

At the feed in position which is shown in Figures 6 and 7, where the rotation of the cylinder is checked by the member 19, the levers 78 are raised. This is effected by the cams 20 on the ends of the cylinder which engage rollers 83 mounted upon stems 84 which pass through the ends 85 of a bar 86. The bar 86 acts when the rollers 83 are raised on the undersides of the levers 78 so as to raise the pressing member 77 from the copy sheet.

After the copy sheet has passed between the pressure rollers and the cylinder 13 it is guided downwardly at the back of the cylinder by guides 88 and 89 and is discharged at the lower part of the front of the machine with the matter reproduced on the upper side of it.

The frame 25 mounted on the carriage is seen clearly in Figure 5, and incorporates the side members 90 and 91, a back bar 93 and a rod 94.

The feed tray 26 is mounted on the rod 94 and is provided with a sleeve 95 on its underside

which engages the rod 94. A spring 96 is provided on the rod 94 acting between the member 90 and the end of the sleeve 95 and tending to move the tray to the right (Figure 5).

This movement is, however, resisted by a pawl 97 which engages a ratchet rack 98 formed on a bar 99. Near its ends the bar 99 is provided with longitudinal slots 106 through which the attaching screws 107 pass, this arrangement allowing the positioning of the bar to be adjusted as may be desired.

The pawl 97 is provided with a stem 100 having a knob 101. This pawl and stem unit is mounted in a housing 102 containing a spring 103 which urges the pawl into engagement with the rack. The housing 102 is fixed to the underside of the tray. The arrangement is such that the pawl can be withdrawn by pulling the knob 101 so as to allow the tray to be moved to the right.

The tray 26 is of channel section and at its delivery end 104 is provided with a guard plate 105 which keeps the lead-in edges of the copy sheets down on to the surface of the tray. To position the copy sheets 66 in relation to the master sheet on the cylinder I may provide an adjustable bar 92 on the tray 26. To provide for adjustment of the bar 92 the tray may be provided with longitudinal slots 175 engaged by screws 176 on the bar 92. For shorter copy sheets the bar 92 is adjusted to a position nearer the delivery end of the feed tray and for longer copy sheets the bar 92 is adjusted to a position further away from the delivery end of the tray 26.

In the construction shown in Figures 1 to 7, the means for moving the carriage and the parts mounted on it parallel to the axis of the cylinder consist of the shaft 21 having a helical groove 108 adapted to be engaged by a lever 109 pivoted at 110 to one side of the carriage and operable by a finger piece 111. The lever 109 is acted upon by a spring 120 which tends to keep the notched part 121 of the lever in the groove. When the edge of this notched part of the lever engages the groove 108 and the shaft 21 is turned, the carriage will be moved to the right or left. If it is desired to slide the carriage freely in either direction the finger piece 111 is depresser bringing the lever out of engagement with the groove 108.

For turning the shaft bevel gear 112 is provided, the shaft 113 is one of the bevel wheels having a crank 114 by which it may be turned. The shaft 113 is mounted in a bracket 115 attached to the frame of the machine.

The bracket 115 may also have an arm 116 carrying a check device 117, this check device incorporating a spring pressed ball 118 which engages once for each revolution of the crank handle 114 with a boss 119 and checks the movement. The arrangement may be such that one turn of the crank handle 114 moves the carriage to the right or left by an amount equal to the width of one line of the matter to be copied.

Alternative means for moving the carriage parallel to the axis of the cylinder are shown in Figures 8 to 12. In this construction a bracket 120a is fixed to the side of the carriage, and to this bracket is connected a flexible member 121a, this flexible member being wound upon and fixed to a spring actuated drum 122 carried by a bracket 123 secured to one of the plates 12. This arrangement provides a constant pull on the carriage to the right as seen in Figure 8.

Fixed to the end members of the machine 75

frame is a bar 124, this bar extending parallel to the axis of the cylinder and being formed with a rack 125.

Movably attached to the outer side of this bar 124 is a bar constituting a ratchet rack 126. This bar is provided with a number of slots 127, each slot having one end extending upwardly in an inclined direction. This bar 126 is mounted on the face of the bar 124 by means of pins 128 carried by the bar 124. The arrangement is such that if the bar 126 is moved to the left it is raised and then moved horizontally. The bar 126 can be operated by a lever 129 pivoted at 130 to a bracket 131 on the right-hand end member of the machine frame.

Fixed on the front surface of the tank is a block 132, and on the front surface 133 of this block is a pivoted detent 134 acted upon by a spring 135 and engaging a stop 136. It will be seen that if the bar 126 is moved to the left one of the teeth on the bar 126 will engage the nose of the detent 134 and will push the carriage to the left to an extent permitted by the length of the slots 127 which may be equal to the width of one line of the matter to be copied. The carriage can thus be moved to the left as seen from the front of the machine with a step by step movement by operating the lever 129.

Mounted in the block 132 is a vertical spindle 137 and fixed on the top of this spindle above the block 132 is a ratchet wheel 138 with which co-operates a pawl 139 pivoted at 140 on the block 132.

Below the block 132 and loosely mounted on the spindle 137 is a toothed wheel 141 engaging the rack 125, and formed in one with this toothed wheel is a flange 142 to which is pivoted a pawl 143.

Fixed on the lower end of the spindle 137 is a ratchet wheel 144, and formed in one with this ratchet wheel 144 is a second ratchet wheel 145 which is engaged by the pawl 143. It will be seen that each of the three ratchet wheels has only two teeth, but the number of teeth on the ratchet wheels is dependent upon the width of the spacing, and this varies according to the lay-out of the forms to be used on the system. For instance where the ratchet wheels have only two teeth, these correspond with a one inch spacing on the forms, but in the case of a half inch spacing on the forms ratchet wheels having four teeth must be used. Similarly, if the spacing on the forms is two-thirds of an inch then the ratchet wheels would have three teeth each, and if the spacing on the forms is one-third of an inch, then the wheels are each provided with six teeth.

Fixed on the underside of the tank is a bracket 146, and pivoted to this bracket is a key 147, this key having a hub 148 and a finger piece 149. On the hub 148 is a lever arm 150 having a pair of laterally projecting lugs 151 carrying a pin 152 upon which are pivoted two pawls 153 and 154, these two pawls being situated one above the other. Both these pawls are adapted to co-operate with the ratchet wheel 144.

The lower pawl 154 is acted upon by a spring 155 and is provided with an adjustable stop 156.

An adjustable stop 158 may be provided fixed to the bottom of the tank and passing through a slot 159 in one of the arms of the key to limit its movement. The key is further acted upon by a spring 160, the lower end of which is attached to a laterally projecting pin 161, and the upper end of which is secured to a suitable part of

the carriage, or a member thereon, this spring acting to pull the key upwardly.

Normally the pawl 154 engages one of the teeth of the ratchet wheel 144 and prevents the spindle 137 from rotating. Since the ratchet wheel 144 is thus prevented from rotating in the direction of the arrow shown in Figure 10, the teeth of the ratchet wheel 145 engaging the pawl 143 also prevent the toothed wheel 141 from rotating. Thus the carriage is held against movement to the right as seen in Figure 8 under the tension of the flexible member 121.

If, however, the key 149 is depressed, the nose of the pawl 154 moves below the tooth on the ratchet wheel 144, but before it releases the tooth the nose of the upper pawl 153 engages the tooth and holds the ratchet wheel 144 stationary. Thus the downward movement of the key does not result in any movement of the carriage to the right. When the lower pawl 154 has moved away from the tooth of the ratchet wheel 144 it makes a pivotal movement into the position shown in dotted lines in Figure 11, and consequently when the key is released and moves upwardly under the influence of the spring 160 the nose of the pawl 154 comes up on the opposite side of the tooth of the ratchet wheel 144 to that where it was originally situated. The upward movement of the key brings the nose of the upper pawl 153 clear of the tooth of the ratchet wheel 144 so that the ratchet wheel 144, and consequently the spindle 137, now makes a half turn in the direction of the arrows shown in Figures 10 and 11 and is arrested by the second tooth coming into contact with the nose of the pawl 154.

In this way the ratchet wheel 144 is unlocked to make a half revolution, and during this movement the carriage is no longer locked against movement to the right. Consequently it moves to the right by an amount corresponding to one half the circumference of the toothed wheel 141 when it again becomes locked by reason of the engagement of the second tooth of the ratchet wheel 144 with the nose of the pawl 154. Thus the carriage can be caused to travel to the right with a step by step movement by operating the finger piece 149, and each step may be equal to the width of one line of the matter to be reproduced, or any fractional part of one line.

It has already been explained how the carriage as seen in Figure 8 can be moved to the left with a step by step movement by operating the bar 126. A spring 162 operates on this bar 126, one end of the spring being anchored to the bar 124, and the other end of the spring being attached to a pin projecting from the lower edge of the bar 126. Thus when the bar 126 is moved to the left (Figure 12) it operates against the tension of a spring.

Further, the carriage (Figure 8) can be pushed to the left to any desired distance. When the carriage is moving to the left as seen in Figure 8, the spindle 137 is prevented from rotation by the ratchet wheel 138 and its pawl 139. This ratchet wheel permits rotation of the shaft in the direction of the arrow shown in Figures 10 and 11, but prevents rotation in the opposite direction. When the carriage is moved to the left it is necessary for the toothed wheel 141 to rotate, and it can do this as it is loose on the spindle 137 and the pawl 143 simply overruns the teeth of the ratchet wheel 145.

In some cases it may be desired to move the carriage automatically one step to the right

after each rotation of the cylinder 13, and for this purpose the cylinder 13 is provided with a cam 163 which can operate a lever 164 fixed to a cross bar 165, the ends of which are provided with pivots 166 and 167 in the end frames of the machine. When the cam 163 rocks the lever 164 the bar 165 operates the key 147.

It is, however, desirable that it should be possible to put this automatic action of travelling the carriage to the right out of use so that it can be travelled by hand when desired, and for this reason the bar 165 carrying the lever 164 can be moved into two alternative positions in one of which it is positioned to be engaged by the cam 163, and in the other of which it is moved out of the path of the cam.

In order to enable this to be done the bar 165 is movable endwise (see Figure 8) and its pivot 166 is provided with two notches 168, either of which is adapted to be engaged by a spring pressed lever 169 pivoted at 170 and operating to retain the bar 165 in either of its two alternative positions by engaging in one of the two slots 168.

At the opposite end of the bar 165 a knob 171 is provided so that it can be pushed to the left. When this is done the lever 169 automatically moves into the left-hand notch 168.

A spring 172 is provided tending to move the bar 165 to the left as seen in Figure 8.

The bar 165 is further provided with an adjustable abutment 173 which is engaged by the end of the carriage, or a suitable projection on the carriage at a predetermined point in the travel of the carriage to the right. This engagement moves the bar 165 to the right and places the lever 164 out of the path of the cam 163.

In operation should it be required to reproduce only one line or item of the master, then one of the moistening pads and the corresponding pressure roller are moved into the operative position. As regards the others, it is sufficient to withdraw the moistening pads, but it is also preferred to move the corresponding pressure rollers into the inoperative position as the positions of the levers 57 will then give an indication as to which lines are being reproduced.

In Figure 5 two of the levers 57 are shown, but if one of the pressure members is of duplex construction as shown in Figure 3 there will of course be three of these levers.

What I claim then is:

1. A machine of the type described having a guide parallel to the axis of the cylinder, a carriage mounted slidably on said guide, a pressure roller of line or paragraph width on said carriage, a stem carrying said pressure roller, a guide for said stem on said carriage, a spring acting on said stem and urging the roller towards the cylinder, an abutment on said stem, a lever engaging said abutment, said lever acting as a stop to limit movement of the stem under pressure of said spring and being capable of moving the roller into an inoperative position, and means for moistening the copy sheets.

2. A machine according to claim 1, comprising a stem guide which is threaded externally and rotatably mounted on the carriage, means for preventing axial movement of the guide, a shoulder on the stem, a nut on the guide thread, and means to prevent said nut from rotating, the spring acting between the nut and the shoulder, whereby the pressure of the spring can be adjusted by turning said guide.

3. A machine of the type described having a carriage mounted on guides for movement parallel to the axis of the cylinder, the carriage having thereon a pressure roller of line or paragraph width, a moistening member of approximately paragraph width, said moistening member being mounted for movement manually in and out of the operative position, and a pressing member for pressing the copy sheets against the moistening member, said pressing member being automatically raised from its operative position once each revolution of the cylinder, wherein the pressure roller is mounted for rotation on the end of a stem slidable in a guide and pressed endwise by a spring, the stem passing through a rotatable sleeve which is screwed upon its exterior, and a nut threaded on said sleeve and forming an abutment for one end of the spring, whereby the rotation of the sleeve will adjust the pressure of the spring.

4. A machine of the type described having a moistening member comprising a tank for containing moistening liquid, said tank having an opening at the top, a table above said opening, a plurality of absorbent moistening pads of line or paragraph width slidable mounted on the table, a casing partially enclosing each pad, a handle on each casing, so that the pads can be individually moved in and out of the operative position, a wick in the tank, and a support for the wick adapted to hold it in contact with the underside of any of the pads which is in the operative position.

5. A machine according to claim 4, wherein the wick support is in the form of a cam, a spindle for said cam, and means whereby said cam may be turned about the axis of the spindle, said cam controlling the area of contact between the wick and the pad.

6. A machine according to claim 4, wherein the wick support is in the form of a cam, a spindle for said cam, and means whereby said cam may be turned about the axis of the spindle, said cam controlling the pressure between the wick and the pad.

7. A machine of the type described having a guide parallel to the axis of the cylinder, a carriage mounted slidably on said guide, a plurality of pressure rollers of line or paragraph width on said carriage, a corresponding number of moistening members of substantially corresponding width on the carriage, a pair of levers pivoted on the ends of the carriage, a pressing bar forming the pressing member, carried by said levers, a pair of levers on the sides of the machine frame, a lifting bar carried by said levers, means for raising said levers on the frame once each revolution of the cylinders, said lifting bar acting upon the said levers on the carriage so as to lift them.

8. A machine of the type described having a guide parallel to the axis of the cylinder, a carriage mounted slidably on said guide, a plurality of pressure rollers of line or paragraph width on said carriage, a corresponding number of moistening members of substantially corresponding width on the carriage, said moistening members being mounted for movement in and out of the operative position, and a feed tray for copy sheets permanently mounted on the carriage but adjustable thereon parallel to the axis of the cylinder, the feed tray being capable of use for

feeding copy sheets to a single moistener or to a plurality of moisteners simultaneously.

9. A machine of the type described having a guide parallel to the axis of the cylinder, a carriage mounted slidably on said guide, a plurality of pressure rollers of line or paragraph width on said carriage, a corresponding number of moistening members of substantially corresponding width on the carriage, said moistening members being mounted for movement in and out of the operative position, a pressing member for pressing the copy sheets against any moistening member which is in the operative position, means for automatically moving the pressing member out of its operative position once each revolution of the cylinder to allow of the insertion of a copy sheet, spring means for moving the carriage in one direction parallel to the axis of the cylinder, key operated mechanism for controlling such movement, a cam associated with the cylinder, and actuating mechanism for the key, said cam co-operating with said actuating mechanism.

10. A machine according to claim 9, wherein the actuating mechanism is movable into a position in which it is not operated by the cam.

11. A machine according to claim 9, wherein the actuating mechanism comprises a bar disposed parallel with the axis of the cylinder, said bar being pivotally mounted on the machine about an axis parallel to its length, a lever arm on said bar adapted to be engaged, in one position of the bar, by the cam on the cylinder, said bar when moved pivotally, operating said key, and said bar being manually movable in an endwise direction to bring the lever arm out of the path of said cam.

12. A machine according to claim 9, wherein the actuating mechanism comprises a bar disposed parallel with the axis of the cylinder, said bar being pivotally mounted on the machine about an axis parallel to its length, a lever arm on said bar adapted to be engaged, in one position of the bar, by the cam on the cylinder, said bar when moved pivotally, operating said key, an adjustable abutment on said bar, means on the carriage to engage said abutment so as automatically to move the lever arm out of the path of the cam on the cylinder at the end of the travel of the carriage.

13. A machine of the type described having a guide parallel to the axis of the cylinder, a carriage mounted slidably on said guide, a plurality of pressure rollers of line or paragraph width on said carriage, a corresponding number of moistening members of substantially corresponding width on the carriage, said moistening members being mounted for movement in and out of the operative position, a pressing member for pressing the copy sheets against any moistening member which is in the operative position, and means for automatically moving the pressing member out of its operative position once each revolution of the cylinder to allow for the insertion of a copy sheet, a manually operable lever associated with each pressure roller for moving it in and out of the operative position, means for retaining each pressure roller in the inoperative position, and a support for a line indicator sheet said levers being disposed adjacent said support so that they can co-operate with a sheet thereon.
